UNITED STATES PATENT OFFICE.

ALPHONSE LOUIS CRONEAU, OF PARIS, FRANCE.

PORTABLE ELECTRICAL DRILLING-MACHINE.

SPECIFICATION forming part of Letters Patent No. 634,165, dated October 3, 1899.

Application filed June 23, 1899. Serial No. 721,674. (No model.)

To all whom it may concern:

Be it known that I, ALPHONSE LOUIS CRO-
NEAU, a citizen of the French Republic, resid-
ing at Paris, Department of the Seine, France,
have invented certain new and useful Im-
provements in Portable Electrical Drilling-
Machines, of which the following is a specifi-
cation.

My invention relates to a portable electrical
drilling-machine for readily drilling flat metal
sheets or plates.

The machine is intended to perform drilling
operations similar to those of drilling-
machines of present construction that oper-
ate with magnetic adhesion to the plate to be
drilled; but my improved machine has the
advantage over these of great lightness,
cheapness, and portability, and is especially
adapted for a class of work for which the said
machines are not well adapted. The said
machines of present construction are heavy
and require several men to work them, where-
as my improved machine has the whole of its
working parts combined in a compact man-
ner, so that it can be readily moved about
and worked by a single operator, being spe-
cially applicable for drilling flat metal sur-
faces, such as the iron decks of ships or floor-
plates of bridges and the like.

I will describe the construction of the im-
proved machine with reference to the accom-
panying drawings, in which—

Figure 1 shows a side elevation of the ma-
chine; Fig. 2, a plan; and Fig. 3, a cross-sec-
tion on line A B, Fig. 1.

The same numerals of reference represent
the same parts in each of the figures.

The machine consists of a metal plate 1,
which carries the whole of the parts consti-
tuting the drilling-machine. To the under
side of this plate in the same vertical plane
as the drilling-tool are fixed two electromag-
nets 3, capable of producing on a plate of
about ten millimeters an adhesion of from five
hundred to six hundred kilos, sufficient for
drilling holes of thirty to forty millimeters.
The drill-carrier 2 is directly actuated by the
electromotor through an elastic coupling 5
without the intermediary of a flexible mem-
ber and in using the ordinary means of me-
chanical connection.

The resistances and the starting and con-
trolling commutator 6 for the motor 4 are
fixed in front in convenient position for the
operator. The current required for the ad-
hesion electromagnets is supplied through
the same commutator, the wires being con-
nected to the first contact after that for stop-
ping.

The drilling-tool 10 is carried in the usual
manner by the tool-carrier 2, and its down-
ward motion is regulated in the usual manner
by a screw-spindle with hand-wheel 11.

The combined apparatus is supported on
the one hand by the electromagnets 3 and on
the other hand by a wheel 9 of the same
height as the electromagnets, so that the drill-
ing-tool is always perpendicular to the plane
passing through the bases of the two electro-
magnets and the under side of the wheel.

The machine is moved by means of the han-
dles 7, which support a wooden plate 8, which
constitutes a seat for the operator, who thus
has the drill and the controlling-commutator
conveniently before him. The weight of the
operator balances that of the motor 4 rela-
tively to the fulcrum formed by the electro-
magnets, and their weight consequently as-
sists the magnetic adhesion.

The above-described machine is particu-
larly useful for drilling flat sheets or plates
for metal floors and decks of ships. As be-
fore stated, a single workman can move and
operate the machine, while all other similar
machines require at least two men. It does
away with the flexible connection which is
necessary with the ordinary drilling-machines
with magnetic adhesion.

Having thus described this invention and
the best means I know of carrying the same
into practical effect, I claim—

Apparatus for drilling metal sheets or
plates, in particular flat metal sheets, with
magnetic adhesion device for keeping the sur-
face to be drilled against the drilling-tool,
consisting of the combination with a metal
platform suitably supported by a single wheel
and two electromagnets constituting the feet
of the machine, and serving to produce the
requisite adhesion of the machine to the sur-
face, to be drilled, a bracket carrying the
drilling-tool fixed on the platform immedi-

ately over the electromagnets so that the drill operates between these, an electromotor fixed on the rear part of the platform connected to the driving-shaft of the drilling-tool by an elastic coupling resistance and a commutator included in the supply-circuit of the motor and electromagnets, carried on the front part of the platform and handles on the platform carrying a seat for the operator so that

he faces the machine in a convenient position for controlling its action, substantially as herein described.

In witness whereof I have hereunto set my hand in presence of two witnesses.

ALPHONSE LOUIS CRONEAU.

Witnesses:

EDWARD P. MACLEAN,
JULES FAYOLLET.
